DOOR FOR AIRSHIP HANGARS

Franciszek Wasilkowski, Lwow, Poland

Application April 15, 1935, Serial No. 16,447
In Poland April 21, 1934

3 Claims. (Cl. 20—16)

The present invention relates to an improved construction of doors for airship-hangars which has the advantages of being extremely light, cheap to manufacture and easy to operate.

5 A construction embodying the features of the invention is shown in the accompanying drawings in which:

Fig. 1 is a diagrammatic front view of the improved door,

10 Fig. 2 a diagrammatic sectional elevation showing also the end *p* of the airship-hangar,

Fig. 3 a front view partly in section of the end wall of the hangar, the left hand half of the opening being shown closed by means of the 15 improved door.

Fig. 4 is a plan view from above corresponding to Fig. 3 and showing a horizontal section through the end of the airship-hangar.

The door consists of a ring *r* (Figs. 1 and 2) adapted to resist compression and opening 20 stresses, said ring being stiffened by tension members *s*, *s'* which may be steel rods. These tension members are fixed with the outer ends to the ring *r*, the inner ends of the rods being fixed to the 25 ends of a centrally arranged horizontal beam *k*. This beam is adapted to be extended longitudinally for the purpose of spanning the tension members *s*, e. g. by means of screws or the like. The tension members *s* can also be spanned by 30 means of a nave movable on the beam *k*, which nave may be pushed towards the end of the beam *k*. *b* indicates a watertight fabric skin or like member which covers the area within the ring; it is fixed in the centre to the beam *k*, 35 and is attached in a watertight manner upon its whole periphery to the ring *r* by any suitable means.

The ring (Fig. 3 and Fig. 4) leans with its upper and middle portions against the wall of 40 the hangar. In the section *a*, the ring bears against movable door wings *d* which are adapted to swing about vertical axes *i* or to be pushed aside.

The wind causes in the fabric skin *b* and tie 45 rods *s*, radial tension stresses which cause a concentric compression in the outer ring *r*. At the same time the ring *r* is pressed by the wind against the wall.

The ring *r* of the door, may, according to the 50 shape of the hangar, be circular, elliptical, oval, or of a similar shape.

The ring is supported at the ends of the central rod *k* upon struts, *g*, *g*, which cross each other (Fig. 2) and rest with the lower ends each upon a carriage *w*, the two carriages running upon a suitable circular rail track *t*. The struts *g*, *g* are connected by tension members *c*, *c*, *n*. It will thus be seen that the supporting structure consists in a trapeze in which the struts *g*, *g* form the diagonals, whilst the tension members *c*, *c*, *n* and the beam *k* constitute the periphery. The struts *g*, *g* are so constructed at their cross section point *f* that they can take up bending moments at right angles to the plane of the trapeze. (The trapeze is secured against falling by the stiff rod *h*.)

The guide rails which form the track upon which the whole door moves, form a circle and are anchored in the ground. The supporting frame *g*, *c*, *n* with the whole door may be moved sideways about the vertical axis *I* for instance by 20 an electromotor *e* with cog-wheels because the stiff rod *h* is anchored in the ground by means of a revolving bearing *O* which is situated in the centre of the circular track *t*.

I claim:

1. A door for airship-hangars, comprising in combination: an outer ring; radial spanned tension members stiffening and compressing said ring; and a central beam for spanning said radial tension members.

2. A door for airship-hangars, comprising in combination: an outer ring; radial spanned tension members stiffening said ring; a central beam for spanning said radial tension members; a supporting frame upon which the said central beam is mounted; and a track upon which said supporting frame is adapted to travel by means of carriages.

3. A door for airship-hangars, comprising in combination: an outer ring; radial spanned tension members stiffening said ring; a central beam for spanning said radial tension members; a supporting frame upon which the said central beam is mounted; a track upon which said supporting frame is adapted to travel by means of 40 carriages, said track being circular; and a stiff rod anchored in the ground in the center of the said circular track and securing the said supporting frame against falling.

50
FRANCISZEK WASILKOWSKI.
